UNITED STATES PATENT OFFICE.

EDWARD KRUSIUS, OF NEW YORK, N. Y.

FOLDING TYPE-WRITER.

Specification of Letters Patent. Patented Nov. 12, 1918.

1,284,714.

Application filed May 8, 1918. Serial No. 233,280.

To all whom it may concern:

Be it known that I, EDWARD KRUSIUS, a citizen of the United States, and a resident of the city of New York, borough of Manhattan, in the county of New York and State of New York, have invented a new and Improved Folding Type-Writer, of which the following is a full, clear, and exact description.

10 This invention relates to typewriting machines and has particular reference to machines of this character that are adapted for the greatest convenience in transportation or traveling, and to this end the machine is made so as to fold into the smallest possible space.

Among the distinct objects of the improvement is to provide a frame or base jointed or hinged transversely so as to fold 20 so that the front portion thereof may fold upward around a horizontal axis parallel to the keyboard.

Another object of the invention is to provide improved locking means to hold the base in rigid flat operative position, but 25 providing for the upward folding as just described.

Another object of the invention is to provide facilities in a foldable frame structure 30 for locating the capital and figure shifting key levers as well as the marginal stop release and back spacing lever in line with the usual or standard keys so that all of the keys or levers will be arranged in the smallest 35 possible number of rows along the keyboard.

A still further object is to provide an improved foldable space key lever holder.

A still further object is to provide a jointed or foldable arm for the capital or 40 figure shifting key levers.

With the foregoing and other objects in view the invention consists in the arrangement and combination of parts hereinafter described and claimed, and while the invention is not restricted to the exact details 45 of construction disclosed or suggested herein, still for the purpose of illustrating a practical embodiment thereof reference is had to the accompanying drawings, in which 50 like reference characters designate the same parts in the several views, and in which—

Figure 1 is a plan view of sufficient of a typewriting machine to illustrate the foldable keyboard portion, parts being in normal 55 operative position.

Fig. 2 is a bottom plan view of the same.

Fig. 3 is a central sectional view about on the line 3—3 of Fig. 1.

Fig. 4 is a vertical sectional detail about on the line 4—4 of Fig. 2, showing particularly the releasing of the locking bar automatically when the keyboard is brought down in operative position.

Fig. 5 is a side elevation of the keyboard folded upward and indicating the automatic action of the locking bar to hold the key levers from displacement when tilted upward and also indicating the folding action of the lever associated with the capital and figure shift levers.

Fig. 6 is an inverted perspective view of a detail indicating especially the automatic catch means for locking the keyboard down in flat operative position, the view, however, indicating the folded position of the parts; and

Fig. 7 is a detail view indicating the folding lever associated with the capital and figure shift keys.

In illustrating my new devices I indicate 80 certain parts similar to corresponding parts of a well known type of typewriter to which my improvements are especially adapted to co-operate, but it is to be understood that I do not intend to be limited or restricted in 85 the use of my improvements with any particular type of machine.

The main part of the base frame 10 may be of any style or design to correspond with the general type of the machine, and with 90 the particular mechanism supported upon the central or rear portions thereof I am not at the present time especially concerned. At the front edge of the base 10 I provide uprights or standards 11 in which are fitted 95 co-axial pivots 12. 13 indicates the keyboard extension of the base 10 the same being provided with uprights or standards 14 shown as lying between the standards 11 and mounted upon the pivots, the pivots 12 constituting the axis around which the keyboard extension 13 is adapted to fold upward into a position approximately perpendicular to the base 10.

With reference now especially to Figs. 2 105 and 6 I point out the construction and operation of the improved automatic catch means for holding the keyboard extension 13 flat and rigid in operative position. The front corner portions 15 of the base 10 are 110 provided with grooves 16 into each of which a finger 17 constituting a rearward exten-

sion of the extension frame 13 is adapted to project in the flat position as shown in Fig. 2 whereby the frame and its extension as a whole is made exceedingly rigid. In other words even though the pivots 12 might be somewhat loose the fingers 17 fit into the grooves 16 rendering it impossible for any freedom of movement between the frame parts 10 and 13. 18 indicates a catch operating in a plane parallel to and just below the plane of one of the grooves 16 and adapted to oscillate around a vertical pivot 19. This catch includes a hook 20 at one end which lies normally over the finger 17 between it and the groove 16, the catch occupying this position by virtue of an expansion spring 21 acting between one of the rigid feet 22 of the main frame 10 and the finger piece 23 at the opposite end of the catch 18. The finger piece as indicated in Figs. 1 and 2 is accessible on one side of the frame whereby when it is pressed inward compressing the spring the hook will be released or withdrawn from a pin 24 carried by the finger 17. From the position of Fig. 6 the end of the finger 17 coming into or toward the groove 16 will first strike against the rounded cam edge of the hook and so cause the hook or catch to swing outward compressing the spring 21. The cam end of the hook is struck first by the end of the finger at about the point 24, but while this point 24 is swinging through the arc of a circle around the pivot 12 and the hook 20 is swinging in a similar arc on its pivot 19 the hook passes over the diagonal corner and wipes over the portion 25 of the finger so that the free end of the finger 17 will not be obstructed in its movement into the groove 16. By the time the finger is nested in its groove the hook will be lying flat on the outside of the finger and in position to swing around the pin 24 as shown in Fig. 2. The catch has a tail piece 26 which striking against the foot 22 will limit the outward movement of the finger piece 23 in the idle or unlocked position of the device.

The standard key levers 27 are shown pivoted upon knife edge bearings 28 for the sake of lightest possible action. The key levers are projected forward through the vertical slots 29 of the bar 30 at the front edge of the frame extension 13 and are adapted to have contact adjacent to their rear ends through the lugs 31 with a universal bar 32. So far as now described the levers 27 are more or less free to slip into or out of normal operative position and so when the keyboard is folded or bent upward some means must be provided to prevent the accidental shifting or dropping out of place of these key levers. To accomplish this result, therefore, I provide what I term a locking bar 33 which lies over the key levers and in spaced parallel relation thereto as shown in Figs. 3 and 4 when the machine is in operation. This bar is shown as lying preferably over the upper edge of a comblike rib 34 having vertical slots in which the rear ends of the levers operate. The ends of the bar 33 are indicated at 35 as projecting downward through pairs of vertically aligned guides or keepers 36 fixed to the rear walls of the hinge standards 14. Each of the ends 35 of the bar 33 is provided between the keepers 36 with a fixed lug 37 between which and the upper keeper 36 is located a spring 38 acting downward against the lug 37 and so tending to carry the adjacent end 35 of the bar in the same direction. Comparing now Fig. 4 with Figs. 5 and 6 it will be noted that when the machine is folded the springs 38 act to throw the lugs 37 toward or against the lower keepers 36 bringing the bar 33 directly against the upper edges of the levers 27, the points of the end portion 35 of the bar at such time projecting well beyond the under surface of the frame extension 13. This action of the springs 38 takes place immediately after the extension 13 starts on its upward folding movement so that there is no possibility for any key levers to drop out of place from the knife edge bearing supports 28 when the frame is folded. When the keyboard is brought back again, however, to its horizontal or operative position, and coincidentally with the automatic action of the locking catch to hold it in locking position as already described the points of the end portions 35 strike and wipe against the upper surfaces of a pair of fingers 39 fixed to and projecting forward adjacent to the inner edges of the corner extension 15 of the base 10 and so with the locking of the extension in place the locking bar 33 will be automatically released, against the force of the springs, from contact with the key levers 27. It will thus be seen that all the operator has to do in bringing the keyboard extension down into operative position is simply to grasp it and swing it around its pivots 12.

In order to conserve the greatest amount of space the frame extension 13 is not provided with a rigid foot, but in lieu thereof I provide a gravity operated foot 40 having upwardly directed parallel extensions 41 pivoted coaxially at 42 on lugs 43 constituting a part of the extension 13. The foot 40 is so hung on its pivots 42 as to drop by gravity automatically into forward position as shown in Fig. 5 so as to lie against the bottom surface of the extension 13 and also to drop automatically into vertical supporting position as shown in Fig. 3 when the extension 13 is brought down into horizontal position. The portions 41 of the foot will be provided with corners 41' which limit the pivotal movement of the foot in a

direction away from its folded position, said corners or shoulders striking against the main part of the frame extension.

The space key lever holder comprises a frame 44 having two forwardly projecting arms 45 and 46, the rear ends of the arms being coaxially pivoted at 47 not far remote from the axis of the pivots 42. The front ends of the arms 45 and 46 are provided with bottom lugs 48 against which a pair of fingers 49 pivoted coaxially of each other at 50 to the respective arms 45 and 46, are adapted to bear in practice, the pivots 50 being at the rear of the lugs 48. The fingers 49, however, which support the spacer bar 51, are free to swing upward and inward around the pivots 50 into the folded position as indicated in Fig. 5.

The capital and figure shift keys are indicated at 52 and 53 at the left side of the keyboard while the marginal stop release and the back space keys are indicated at 54 and 55 at the right side of the keyboard, these several keys being located in alignment with the standard rows of keys indicated generally at 56, there being provided only three rows of keys in this particular machine. This arrangement of keys and accessories therefore adapts itself with peculiar favor to the folding of the machine into the smallest possible space.

While the rear or inner ends of the standard key levers may not extend sufficiently far beyond the vertical plane of the pivots 12 to interfere with the folding movement of the keyboard as shown in Fig. 5, it is to be noted that the keys 52 and 53 operate upon a vertical plunger 57 at about the center of oscillation of a type carrier, (not shown) and lie at a considerable distance back of the hinge line of the frame. The several functions of the keys 52 and 53 are thus carried into effect by means of an arm 58 keyed or otherwise fixed to a horizontal rock shaft 59 just back of the slotted rib 31. A spring 60 surrounds the rock shaft 59 and is so anchored at one end as to cause the opposite end thereof as indicated at 61 to bear downward upon the arm 58. 62 indicates a hub secured upon the rock shaft 59 between the angularly shaped ends of the levers 52 and 53 and provided with a cross pin 63 held normally against the rear edges of the offset portions of the levers by virtue of the spring 60. See Fig. 7. The upward throw of the levers 52 and 53 is limited by the keeper bar 64 lying upon all of the key levers, hence the offset portions of these two levers 52 and 53 constitute a limiting stop for the cross pin 63 while the spring 60 tends to throw the arm 58 downward at its rear end. Since the levers 52 and 53 are otherwise journaled loosely upon the rock shaft 59 it follows that a depression of either of these levers will act in the direction of

the arrow on Fig. 7 to rotate the rock shaft and so lift the rear end of the arm 58 whereby the plunger 57 is lifted to an extent proportional to the extent of downward thrust of the particular lever being actuated. 70 From the construction just described it will be understood that the arm 58 is free to swing upward relatively around the axis of the rock shaft 59 when the keyboard is folded upward or in other words and perhaps more accurately stated the joint provided at the rock shaft between the bar 58 and the levers 52 and 53 will permit the levers to swing upward with the keyboard while the rear end of the arm bearing against the table 80 or other support for the machine, articulates at the rock shaft with respect to the levers 52 and 53 and lies in the position indicated in Fig. 5.

I claim:

1. In a folding typewriter, the combination of a main frame, a keyboard frame extension, a set of keys carried by the extension and movable therewith with respect to the main frame, one of the frame members 90 aforesaid being provided with a pair of rigid fingers while the other of said members is provided with a pair of grooves into which said fingers project when the frame members are in operative position and 95 whereby lateral movement of either with respect to the other of the frame members is prevented, and catch means carried by one of the frame members and co-operating with the other to prevent separation of the finger 100 and groove portions of the frame.

2. In a folding typewriter, the combination of a rigid main base frame, the front corners of which are provided with a pair of grooves on the lower surface, a keyboard 105 frame extension movably connected to the main base frame for folding purposes, said extension having a pair of rigid rearwardly extending fingers at its lower surface fitting into said grooves when the extension is in 110 operative position with respect to the main base frame, and automatic catch means co-operating with the several frame members to hold the fingers in said grooves.

3. In a folding typewriter, the combination of a main base frame, a keyboard frame extension pivoted to the main base frame along its front edge and foldable upward around the axis of the pivots, one of the base members being provided with parallel 120 grooves on its lower surface while the other of the base members is provided with parallel fingers co-operating with the grooves in normal operative position, and an automatic spring catch carried by the grooved 125 member and engageable over one of said fingers to lock the frame members from movement with respect to each other around the pivots aforesaid.

4. In a folding typewriter, the combina- 130

- tion with a main frame, a frame extension movably connected thereto and a set of key levers loosely supported upon the frame extension, of means normally spaced from the 5 key levers but automatically movable into contact therewith to hold the levers from displacement when the frame extension is moved with respect to the main base member.
- 10 5. In a folding typewriter, the combination with a main stationary base frame, a keyboard frame extension movably connected to the stationary base for folding purposes and a set of key lever loosely fulcrumed 15 upon the frame extension for normal operation of the machine, of locking means cooperating with the key levers and serving to hold them from all movement with respect to the frame extension when the machine is folded, and means to automatically withdraw said locking means from the levers when the frame extension is returned to normal operative position.
6. In a folding typewriter, the combination 25 with a main base frame, a keyboard frame extension pivoted thereto for upward folding movement and a set of key levers loosely fulcrumed upon the extension for operative movement, of a locking bar extending across and normally spaced above said 30 key levers, means acting upon the bar serving to bring the bar automatically into contact with the key levers to hold them from movement with respect to the frame extension when the frame is folded, and means carried by the main frame serving to automatically withdraw said bar from the levers when the frame extension is returned to normal operative position.
- 40 7. In a folding typewriter, the combination with a main base frame, a keyboard frame extension pivoted thereto for folding purposes and a set of key levers carried by the extension and foldable therewith with 45 respect to the main frame, of a shift key lever carried by the frame extension, a rock shaft journaled upon the rear portion of the frame extension, the rear end of the shift key lever being journaled upon the rock 50 shaft, an arm extension connected to the rock shaft and projecting rearward beyond the vertical plane of the folding axis, and means between the shift key lever and rock shaft serving to cause the vertical movement of the arm extension when the shift key lever is depressed, but freely permitting the folding movement of the shift key lever with the frame extension independently of said arm extension.
8. In a folding typewriter, the combination with a main base frame, a frame extension pivoted thereto for upward folding movement, and a set of key levers carried by the frame extension and foldable therewith, of a plurality of shift key levers foldable 60 with the frame extension, a rock shaft journaled upon the frame extension and upon which the shift key levers are journaled, a rearwardly projecting actuator arm connected to the rock shaft, and a hub connector 65 between the rock shaft and the shift key levers serving to cause the upward movement of the actuator arm when either of the shift key levers is depressed independently of the other and permitting 70 the upward movement of the frame extension and parts carried thereby independently of the actuator arm.
9. In a folding typewriter, the combination with a main frame having rigid feet 80 to support the same in elevated position, and a frame extension pivoted to the main frame and foldable upward with respect thereto, of a foot pivotally connected to the frame extension and serving in normal position to 85 support the extension in the same horizontal plane as the main frame, but foldable into a position close against the frame extension when the extension is folded.
10. In a folding typewriter, the combination with a main frame and a frame extension pivoted thereto adapting it to be operated upward with respect to the main frame, of a supporting foot freely pivoted to the frame extension whereby when the 95 frame extension is folded upward the foot drops thereagainst by gravity and when the frame extension is brought down into operative position said foot drops automatically into supporting position.

EDWARD KRUSIUS.
